UNITED STATES PATENT OFFICE

GEORGE G. CHALMERS, OF HUNTINGTON BEACH, CALIFORNIA

WELL DRILLING BIT

Application filed October 5, 1929. Serial No. 397,568.

This invention relates to a drilling tool and relates more particularly to a well drilling bit.

In drilling wells, such as oil wells, with the rotary method, the drilling tool or bit is operated through a drill stem consisting of lengths of drill pipe joined together end to end. As the well is drilled, casing is set in the bore and the drill stem is operated with-
 10 in or through the casing. When it becomes necessary to replace or repair a drilling tool, the entire drill stem must be withdrawn from the well. The drill stem is uncoupled as it is withdrawn and the lengths or stands of pipe are stacked in the derrick. The with-
 15 drawing of the drill stem and the uncoupling of the stands of drill pipe require much time and are therefore costly operations. Further, to resume drilling the drill stem must be
 20 again coupled together and lowered into the well.

It is a general object of the invention to provide a well drilling bit that is adapted to be operated at the lower end of the well casing. The bit provided by this invention is adapted to be operated at the lower end of a tubular member, say, the usual well casing, and does not necessitate employing a
 25 drill stem.

Another object of the invention is to pro-
 30 vide a drilling bit of the character mentioned which can be readily attached to a shoe at the lower end of the well casing within a well and may be detached from the shoe when desired.

Another object of the invention is to pro-
 35 vide a well tool of the character mentioned that is adapted to drill a hole which will freely pass the casing. The bit provided by this invention eliminates the necessity of using underreamers and permits casing of large diameter to be run a maximum depth in the well.

Another object of the invention is to pro-
 40 vide well tool of the character described in which the cutters are replaceable.

Another object of the invention is to pro-
 45 vide a well tool of the character mentioned which may embody any desired type of guide

or pilot bit; for example, it may embody any suitable form of drag bit, core drill, etc.

It is another object of the invention to pro-
 50 vide a bit of the character mentioned that is adapted to be detachably connected to a shoe on the lower end of well casing and is adapted to be detached from the shoe through engagement by an overshot, or the like, op-
 55 erated on a cable or line.

Other objects and features of my inven-
 60 tion will be best and more fully understood from the following detailed description of a typical form and application of the inven-
 65 tion, throughout which description reference is had to the accompanying drawings, in
 which:

Fig. 1 is a side elevation of the bit pro-
 70 vided by this invention showing the cutters in the operating position. Fig. 2 is a side elevation of the shoe provided by this inven-
 75 tion showing certain parts broken away. Fig. 3 is a longitudinal detailed sectional view of the bit in position within the shoe ready to be set. Fig. 4 is a side elevation illus-
 trating the bit in operating position. Fig. 5 is a detailed transverse sectional view taken substantially as indicated by line 5—5 on Fig. 4.

The well tool provided by this invention includes, generally, a shoe 10 adapted to be attached to the lower end of a string of well casing and a bit proper A including a body 11 adapted to be lowered into the shoe 10, a sleeve 12 longitudinally shiftable on the body, a stem 13 on the sleeve operable through its weight to shift the sleeve downward relative to the body, means 14 for releasably connecting the shoe and body 11 against relative longitudinal movement, cutters 15 pivotally mounted on the body 11 shiftable between retracted positions and extended positions, means 16 connecting the sleeve 12 and the cutters 15 whereby the cutters are operated to the extended positions when the sleeve 12 is shifted downward relative to the body, and a pilot cutter 11^a on the lower end of the body.

The shoe 10 is permanently attached to the lower end of the well casing and may be attached to the casing in any desired manner. In accordance with the invention the shoe 10

acts as a part to which the bit proper may be releasably secured. The shoe 10 is an elongate cylindrical member having a longitudinal opening 17 extending completely throughout it. The opening 17 is preferably of substantially the same diameter as the opening in the well casing and it is further preferred that the walls of the shoe 10 be somewhat thicker than the walls of the casing 5 so that the shoe has a larger outside diameter than the casing. The exterior of the shoe 10 is preferably of uniform diameter throughout its length. The lower end of the shoe 10 is provided with three stops 18 in the form of vertical shoulders. The shoulders or stops 15 18 are equally spaced around the lower end of the shoe and face forward relative to the direction of rotation of the shoe during drilling operations. The walls of the opening 17 are provided with a raised or inwardly projecting portion 19 provided in its upper edge with recesses 20. The edges of the recesses 20 diverge upwardly so that the recesses are substantially V-shaped. The portion 19 and the recesses 25 20 act as guides to properly position the body 10, as will be hereinafter described. An annular recess or groove 21 is provided in the wall of the opening 17 above the projecting portion 19. It is preferred that the upper and lower walls of the groove 30 21 be at right angles to the longitudinal axis of the opening 17.

The body 11 of the bit proper A is elongate and cylindrical in its general configuration 35 and is adapted to fit within the opening 17 of the shoe 10. The body 11 includes a central portion 22, a lower portion 23, and an upper extension or upper portion 24 of reduced diameter. A circulation opening 25 extends completely through the body 11 extending longitudinally through the three body portions. The central portion 23 is round in cross section and is provided with guides 26 to cooperate with the recesses 20 in 40 the shoe to properly position the body 11 in the shoe 10. The guides 26 have downwardly convergent edges to cooperate with the walls of the recesses 20.

The lower portion 23 of the body 11 is of 50 triangular cross section having three vertical sides 27. In accordance with the invention the lower portion 23 of the body projects a considerable distance below the lower end of the shoe 10 when the body 11 is in operating position in the shoe. The lower end of the portion 23 is provided with a reduced screw threaded pin 28 to which any desired type of pilot cutter or bit may be attached. The cutters 15 are pivotally mounted on the 55 vertical faces or sides 27, as will be herein-after described.

The upper portion 24 of the body is of considerably less diameter than the central portion 22 so that the upper end of the portion 60 22 presents an upwardly facing shoulder 30.

The upper end of the central portion 22 may be provided with a socket 31 and the lower end of the portion 24 may be screw threaded into the socket. An outwardly extending radial flang or enlargement 32 is provided on 70 the upper end of the upper portion 24.

Any suitable type or form of pilot bit may be attached to the lower end of the body. In the particular form of the invention illustrated in the drawings I have shown a core 75 drill 33 screw threaded onto the pin 28. The core drill includes a body 34, cutters 35 projecting radially from the body 34, an annular core cutter 36 at the lower end of the body 34, and a core tube or barrel 37 projecting upwardly in the opening 25. Fluid passages 37^a are provided in the body of the core drill to discharge fluid from the opening 25. The core drill 33 just described is a typical form of drill, and the invention is not to be considered as limited to this particular type of drill for a pilot or guide bit.

The sleeve 12 is longitudinally shiftable on the upper portion of the body 11 between the shoulder 30 and the flange 32. The sleeve 12 preferably has a curved exterior and freely fits within the shoe 10. The upper end of the sleeve 12 is provided with a socket 35 having a bottom or lower end which engages the flange 32 to limit the upward movement of 85 the sleeve.

The stem 13 projects upward from the upper end of the sleeve 12 and is provided to carry or depend the body 11 from a cable or line and to shift the sleeve 12 downward relative to the body 11 when the body is in position in the shoe 10 and the cable is released from the stem 13. The stem 13 is tubular and is comparatively long, extending a considerable distance upward into the casing. In 105 practice it may be convenient to form the stem 13 of lengths of drill pipe. The upper end of the stem 13 is provided with a releasable cable connection which is not illustrated in the drawings, connections of this type 110 being well known to those skilled in the art. The lower end of the stem 13 may be screw threaded into the socket 35. The stem 13 is of sufficient weight to cause downward movement of the sleeve 12 when the body 11 is in 115 position in the shoe and the cable is released from the stem.

The means 14 for releasably connecting the body 11 and the shoe against relative longitudinal movement is actuated by the downward shifting of the sleeve 12 relative to the body 11. The means 14 includes a resilient expandible ring 37 arranged around the portion 24 of the body adjacent the shoulder 30. The ring 37 may be formed of rubber composition, or the like, and is positioned in alignment with the groove 21. The ring is shaped to readily enter the groove and its inner side is inclined upwardly and outwardly. A plurality of spaced metal inserts or blocks are 120 125 130

provided on the outer side of the ring 37. The ring is connected to the body 11 by leaf springs 40 attached to the inner sides of the blocks 39 and attached to the central portion 22 of the body. The ring 37 is expanded by wedge means when the sleeve is shifted downward relative to the body. An annular wedge part 41 is provided on the lower end of the sleeve 12 to cooperate with the inner side of the ring. The outer side of the wedge part 41 is tapered upward and outward to engage the tapered inner side of the ring and expand the ring radially.

The invention provides means for cushioning the downward movement of the sleeve 12 and for resisting the tendency of the fluid pressure in the casing to prematurely shift the sleeve downward. A coiled spring 42 is arranged under compression between the shoulder 30 and lower end of the sleeve 12. The spring 42 normally yieldingly urges the sleeve upward.

The cutters 15 may be in the form of blade cutters and are pivotally mounted on the vertical faces 27 of the lower portion of the body. There are preferably three cutters 15, one cutter mounted on each face 27. The cutters are shiftable between positions where they do not project from the body and actuated positions where their cutting parts project laterally from the body. The cutters 15 may be flat and are pivotally mounted on studs 43 projecting laterally from the faces 27. Each cutter 15 includes an inner portion having an opening 46 passing the stud 43 and a cutting portion 47. The cutters 15 are retained on the studs 43 by means of retaining nuts 48 screw threaded on the studs. Keys 49 may be provided to lock the nuts 48 on the studs. The cutting portion 47 of each cutter projects from the inner portion so that it is shifted from a position adjacent the face 27 to a position where it projects from the body when the cutter is partially rotated.

It is an important feature of the invention that the body 11 be positioned in the shoe 10 by the guides 26, and the cutters are located so that when the cutters 15 are actuated to the extended positions they are adjacent to, or in engagement with, the stops 18. This position of the cutters is clearly illustrated in Fig. 4 of the drawings. The cutters thus arranged are effectively supported against rotative strains during operation of the tool. With this construction the studs 43 are not subjected to undue strain and the cutters are always easily shifted or rotated.

The means 16 for connecting the cutters 15 with the sleeve 12 includes a rod 50 pivotally attached to each cutter and secured to the sleeve. The upper ends of the rods 50 may be screw threaded into openings in the lower end of the sleeve. The rods project downwardly from the sleeve and extend through longitudinal openings 51 in the cen-

tral portion of the body. The rods extend completely through the portion 22 of the body and their lower ends are flattened. The flattened lower ends of the rods 50 extend between yoked parts 52 of the cutters 15. Pivot pins 53 extend through openings in the yoked parts 52 and the flattened portions of the rods 50 and pivotally connect the rods and cutters. The yoked parts 52 project from the inner portions of the cutters and the rods 50 are pivotally attached to the cutters at points offset from the axes of rotation of the cutters. The rods 50 are connected to the cutters in a manner to cause the cutting portions 47 of the cutters to be swung outward when the sleeve 12 is shifted downward.

It is believed that the operation of the bit provided by this invention will be understood from the foregoing detailed description. The shoe 10 is permanently attached to the lower end of the casing before it is run into the well bore. When the casing is placed in the well the bit A is lowered into the casing by means of a cable, or the like, removably attached to the stem 13 by a releasable cable connection. When the body 11 reaches the shoe 10 the guides 26 cooperate with the recesses 20 to properly position the body 11 in the shoe. The weight of the body 11 and other parts is sufficient to maintain the sleeve 12 in the up position during the lowering of the tool through the casing so that the cutters remain in the retracted position. When the body 11 is set or positioned in the shoe 10 the cable or line is released from the stem and the stem is permitted to move downward. The downward movement of the stem 13 and the sleeve 12 shifts the wedge part 41 into engagement with the tapered side of the ring 37 and expands the ring and blocks 39 into the groove 21. Downward movement of the sleeve 12 acting through the rods 50 partially rotates the cutters 15 so that the cutting parts 47 are moved into actuating position. The tool is then ready for operation and rotation of the casing and shoe 10 may be started. It is to be noted that the body 11 of the bit proper A is held against longitudinal movement relative to the shoe 10 by the means 14 and that it is held against relative rotative movement by the cooperation of the stops 18 and the cutters 15 and by the guides 26. When it is desired to remove or detach the bit A from the shoe 10 an overshot, or like tool, is operated by a cable or line to engage the stem 13 and is pulled upward. It will be obvious how the resilient ring 37 will return to its normal free position and the cutting parts 47 will be swung to their normal retracted positions when the stem 13 is moved upward.

The cutters 15 are readily removed from the studs 53 for repair or replacement. Any suitable type of pilot bit 11a may be mounted on the pin portion 28 of the body. The

spring 42 acts to yieldingly hold the parts in the unactuated position and to cushion the operation of the sleeve 12.

Having described only a typical, preferred form of my invention, I do not wish to limit myself to the specific details set forth, but wish to reserve to myself any changes or variations that may appear to those skilled in the art or fall within the scope of the following claims.

Having described my invention, I claim:

1. A well tool of the character described including, a shoe adapted to be attached to the lower end of a spring of well casing, and a bit adapted to be passed through the casing including, a body, means for positioning the body within the shoe, means for releasably holding the body and shoe against relative longitudinal movement in either direction, a cutter pivoted on the body, and means for swinging the cutter to a position where it projects from the body when the body is positioned within the shoe.

2. A well tool of the character described including, a shoe adapted to be attached to the lower end of a string of well casing, and a bit adapted to be passed through the casing including, a body, means for positioning the body within the shoe, means for releasably holding the body and shoe against relative longitudinal movement in either direction and against relative rotative movement, a cutter pivoted on the body, and means for partially rotating the cutter to a position where it projects from the body when the body is positioned within the shoe.

3. A well tool of the character described including, a shoe adapted to be secured to the lower end of a string of well casing, a stop on the shoe, and a bit adapted to be passed through the casing including, a body, means for releasably holding the body against longitudinal movement relative to the shoe, a cutter pivotally mounted on the body, cutting parts on the cutter, and means for partially rotating the cutter to operate the cutting parts to a position adjacent the stop.

4. A well tool of the character described including, a shoe adapted to be secured to the lower end of a string of well casing, there being an internal groove in the shoe, and a bit adapted to be passed through the casing, including, a body, means for definitely positioning the body within the shoe, a cutter pivotally mounted on the body, cutting parts on the cutter, and means for releasably holding the body against longitudinal movement relative to the shoe when the body is positioned in the shoe, and for shifting the cutting parts to an extended position projecting from the shoe, said means including a sleeve longitudinally shiftable on the body, means for causing movement of the sleeve, an expansible ring attached to the body and expanded into the groove by movement of the

sleeve, and a rod connecting the cutter and sleeve.

5. A well tool of the character described including, a shoe adapted to be secured to the lower end of a string of well casing, there being an internal groove in the shoe, and a bit adapted to be passed through the casing including, a body, means for definitely positioning the body within the shoe, a cutter pivotally mounted on the body, cutting parts on the cutter, and means for releasably holding the body against longitudinal movement relative to the shoe when the body is positioned in the shoe, and for shifting the cutting parts to an extended position projecting from the shoe, said means including a sleeve longitudinally shiftable on the body, means yieldingly retaining the sleeve in a certain position, means for causing movement of the sleeve, an expansible ring attached to the body and expanded into the groove by movement of the sleeve, and a rod connecting the cutter and sleeve.

6. A well tool of the character described including, a shoe adapted to be secured to the lower end of a string of well casing, there being an internal groove in the shoe, and a bit adapted to be passed through the casing including, a body, means for definitely positioning the body within the shoe, a cutter pivotally mounted on the body, cutting parts on the cutter, means for releasably holding the body against longitudinal movement relative to the shoe when the body is positioned in the shoe, including a sleeve longitudinally shiftable on the body, an expansible ring attached to the body, wedge parts on the sleeve and gravity means for shifting the sleeve so that the wedge parts expand the ring into the said groove, and means for operating the cutter so that the cutting parts project from the shoe.

7. A well tool of the character described including, a shoe adapted to be secured to the lower end of a string of well casing, there being an internal groove in the shoe, and a bit adapted to be passed through the casing including, a body, means for definitely positioning the body within the shoe, a cutter pivotally mounted on the body, cutting parts on the cutter, means for releasably holding the body against longitudinal movement relative to the shoe when the body is positioned in the shoe, including a sleeve longitudinally shiftable on the body, an expansible ring attached to the body, wedge parts on the sleeve and gravity means for shifting the sleeve so that the wedge parts expand the ring into the said groove, and means for operating the cutter so that the cutting parts project from the shoe, last mentioned means including, a rod on the sleeve connected to the cutter.

8. A well tool of the character described including, a shoe adapted to be secured to the lower end of a string of well casing, there be-

ing an internal groove in the shoe, and a bit adapted to be passed through the casing including, a body, means for definitely positioning the body within the shoe, a cutter pivotally mounted on the body, cutting parts 5 on the cutter, means for releasably holding the body against longitudinal movement relative to the shoe when the body is positioned within the shoe including, a sleeve longitudinally shiftable on the sleeve, wedge parts 10 on the sleeve, an expansible ring attached to the body, blocks on ring, and a stem on the sleeve operable through its weight to shift the sleeve downward and cause the wedge parts to expand the sleeve into the groove, 15 and a rod on the sleeve attached to the cutter.

9. A well tool of the character described including, a shoe adapted to be attached to the lower end of a string of well casing, and 20 a bit adapted to be passed through the casing including, a body, means for positioning the body within the shoe, including guides on the body adapted to cooperate with recesses in the shoe, means for releasably holding the body and shoe against relative longitudinal 25 movement in either direction, a cutter pivoted on the body, and means for oscillating the cutter to a position where it projects from the body when the body is positioned within the shoe.

30 10. A well tool of the character described including, a shoe adapted to be attached to the lower end of a well casing, a stop on the shoe facing forward relative to the direction of operation of the casing, and a bit 35 adapted to be passed through the casing including, a body, a cutter pivotally mounted on the body, cutting parts on the cutter, means for definitely positioning the body 40 within the shoe, and means for simultaneously holding the body against movement relative to the shoe and for operating the cutter so that the cutting parts are immediately forward of the said stop.

45 11. A well tool of the character described including, a shoe adapted to be secured to the lower end of a string of well casing, there being an internal groove in the shoe, and a bit adapted to be passed through the casing including, a body, means for definitely positioning 50 the body within the shoe, a cutter pivotally mounted on the body, cutting parts on the cutter, means for releasably holding the body against longitudinal movement relative to the 55 shoe when the body is positioned within the shoe including, a sleeve longitudinally shiftable on the sleeve, wedge parts on the sleeve, an expansible ring attached to the body, blocks 60 on the ring, and a stem on the sleeve operable through its weight to shift the sleeve downward and cause the wedge parts to expand the sleeve into the groove and a rod on the sleeve attached to the cutter, the cutting 65 parts being retracted and the body released

from the shoe upon upward movement of the stem.

12. A well tool including, a shoe adapted to be permanently sectioned to the lower end of a well casing, a plurality of stops on the shoe 70 facing forward relative to the direction of rotation of the casing, and a bit adapted to be passed through the casing including, a body, a plurality of cutters pivotally mounted on the body, means for definitely positioning the body in the shoe, means for releasably holding the body against longitudinal movement relative to the shoe, means for shifting the cutters so that a cutter is immediately forward of each stop, and a pilot cutter on 80 the lower end of the body.

In witness that I claim the foregoing I have hereunto subscribed my name this 26th day of September, 1929.
